BLIND STITCH SEWING MACHINE

Charles W. Mueller, St. Louis, Mo., assignor to
 Lewis Invisible Stitch Machine Company,
 St. Louis, Mo., a corporation of Maine

Application November 18, 1931, Serial No. 575,891

8 Claims. (Cl. 112—178)

This invention relates to new and useful improvements in blind stitch sewing machines generally, although more particularly to machines for blind stitching hems along the bottoms of 5 skirts and on other articles of wearing apparel.

Among the several objects of my invention are to provide a hemmer which is located in advance of the ridge forming element and is capable of having its core and scroll relatively 10 adjusted laterally to compensate for materials of different thicknesses, and to vary the distance between the inner edge of the hem and the point of needle penetration; to provide a vertically yieldable auxiliary feed dog section which 15 is disposed directly below the hem for cooperation with the stationary presser foot to accommodate hems of different thicknesses and to feed the same, and to clamp the hem against the foot during the setting of the stitches whereby 20 the hem will be retained against being curled or rolled; and to provide a hemming mechanism of the character described which is simple in construction and durable in operation.

With these and other objects in view which 25 will more fully appear, the nature of the invention will be more clearly understood by following the description, the appended claims and the several views illustrated in the accompanying drawings.

30 In the drawings:—

Figure 1 is a horizontal sectional view taken directly above the stationary presser foot of a blind stitch sewing machine embodying my invention and showing the fabric being hemmed,

35 Figure 2 is a left hand elevation thereof, the stitch forming mechanism and the top feed being omitted.

Figure 3 is a right hand elevation of the construction shown in Figure 1,

40 Figure 4 is a vertical sectional view taken on the line 4—4 of Figure 1,

Figure 5 is a top plan view of the presser foot with the scroll portion of the hemmer removed,

45 Figure 6 is a bottom plan view of the presser foot with the complete hemmer attached thereto,

Figure 7 is a plan view of the work clamp, the ridge forming element, and the feeding means,

50 Figure 8 is a detail cross sectional view taken through the main and auxiliary feed dogs,

Figure 9 is a perspective view of the main feed dog,

55 Figure 10 is a perspective view of the auxiliary feed dog,

Figure 11 is a cross sectional view taken through the front portion of the foot and the hemmer,

Figure 12 is a perspective view of the scroll portion of the hemmer,

5 Figure 13 is a plan view of a hemmed fabric blind stitched by a line of single thread chain stitches, and

Figure 14 is a similar view but showing the hem blind stitched by a line of lock stitches.

Referring to the accompanying drawings, I have shown my invention applied to the well known Lewis single thread chain stitch machine

10 which includes a stitching head A and a work arm B. A stationary presser foot C is rigidly attached to the stitching head, and disposed below the foot and cooperating therewith in the usual manner is a vertically yieldable work

15 clamp D, a 4-motion main feed dog E, and a vertically reciprocating ridge forming element or plunger F which projects a node or ridge of fabric upwardly through an elongated opening 5 formed in the foot C. As shown in Figs. 13

20 and 14, this machine is adapted to form a double fold hem g in the fabric G and secure the same to the body fabric by a line of blind stitches which may be of the single thread chain stitch

25 type as indicated at g' in Fig. 13 or of the lock stitch type as indicated at g² in Fig. 14. Dis-

posed above the foot and supported by the stitching head is the usual blind stitch forming mechanism which may be of any suitable type.

In the present instance, I have disclosed the 30 usual single thread stitch forming mechanism which includes a curved needle 6 and a 6-motion

loop 7, the needle oscillating in a vertical plane which contains the plunger F and is dis-

posed at right angles to the line of feed.

35 The presser foot C at the front end thereof, is provided with a centrally located and rearwardly extending slot 8 forming resultant toe portions 9 and 10 respectively, the slot 8 being

disposed directly in front of the plunger open-

40 ing 5 and communicating therewith through a longitudinal groove 11 formed in the under face of a bridge 12 which integrally connects said toe portions.

Attached to the front end of the presser foot 45 C and projecting into the slot 8 thereof is a hammer H for forming the hem g in the fabric G. This hemmer consists of two portions, a core 13 and a surrounding scroll 14. The core

50 13 projects longitudinally into the slot 8 and terminates at its rear end in spaced relation to

and in front of the groove 11, the longitudinal plane of the core being in substantial registry with the right hand wall 5^a of the opening 5 of

55 the presser foot. The core is provided at its rear end with a laterally extending attaching arm 15

which is mounted in a horizontal opening ex-

60 tending transversely in the toe 9 of the foot and secured therein by a clamp screw 16. The scroll

14 is rigidly connected to a holder 17 which is mounted on the toe 10 of the foot for lateral adjustments. To this end, the holder 17 is provided on its under face with a tongue 18 which 5 engages in a groove 19 formed in a rectangular attaching plate 20. The plate 20 is disposed under the toe 10 of the presser foot and is provided with two openings 21, 21 through which the shanks of clamping screws 22, 22 pass upwardly into threaded openings formed in the toe, the openings being larger in diameter than the screw shanks to permit of the plate being adjusted laterally relative to the toe. The left vertical wall 20^a of the plate extends along side 10 of but in spaced relation to the core 13 and scroll 14 of the hemmer H, and along the right side of but in spaced relation to the right hand wall 5^a of the opening 5 of the foot, and therefore constitutes a vertical guide for the hem for 15 directing the latter from the hemmer past the needle 6 and the ridge forming element F. The shank of a clamping screw 23 passes upwardly through an opening 24 formed in the front end of the plate 20 and engages in a threaded opening 25 in the holder 17, thereby permitting the holder to be adjusted laterally relative to both the plate 20 and the presser foot C.

It will, therefore, be apparent that by laterally adjusting the plate 20, the outer folded edge of 30 the hem g may be variably positioned relative to the line of needle penetration and therefore the distance between the line containing the points of needle penetration and the inner edge of the hem may be varied, and that by laterally 35 adjusting the holder 17 relative to the plate 20, the scroll 14 will be thereby laterally adjusted relative to the core 13 to compensate for the adjustment previously described. It will furthermore be observed that by laterally adjusting 40 the holder 17 relative to the core 13, the capacity of the folder may be varied so as to permit the hemming of fabrics of different weights within certain limits.

The main 4-motion feed dog E as shown in 45 Figure 9, includes a supporting shank 25 to which a relatively long feed surface 26 is integrally attached. This feed dog operates in a feed slot d formed in the work clamp D which is disposed at the left of the ridge forming element or plunger F and extends from a point in front of the bridge 12 of the presser foot to a point in rear of the ridge forming element. Thus the main feed dog section 26 engages the body fabric G and feeds the same rearwardly 50 from the hemmer H past the ridge forming element F. Rigidly connected to the shank 25 of the main feed dog E adjacent the rear end thereof is a laterally extending arm 27 which integrally supports a centrally located and relatively 55 short feed section 28. This feed section 28 is disposed in rear of and in spaced relation to the ridge forming element F and cooperates with the feed section 26 to feed the body fabric rearwardly in rear of said ridge forming element. The feed section 28 is supported on the arm 27 through the medium of a vertical shank 29 and the right hand edge of the feed section 60 overhangs the shank 29 as indicated at 30 in Figure 9 to form a resultant stop shoulder.

70 An auxiliary feed dog X is connected to the main feed dog E and cooperates with the hem g to feed the latter and also to clamp said hem against the presser foot during the setting of the stitches to thereby prevent the hem from being curled or rolled. Furthermore, this auxiliary

feed dog X is yieldably mounted whereby hem folds of different thicknesses due to different weights of materials may be automatically accommodated. The auxiliary feed dog X includes a supporting bar 31 and a relatively long and narrow feed section 32 which is integral or otherwise fixedly secured to the bar. This bar is located above the arm 27 and below the stop shoulder 30, and the rear end of the bar is pivotally connected to the shank 29 by a horizontal pivot screw 33. The rear end of the feed section 32 is cut away to form a limiting stop 34 which is adapted to engage the stop shoulder 30 and thereby limit the upward movement of the auxiliary feed dog relative to the main feed dog. 10 A coil spring 35 has its upper end seated in a recess formed in the bar 31 and the lower end of this spring rests upon the arm 27. Thus the spring 35 which is disposed in front of the pivot screw 33 yieldably retains the stop 34 against the stop shoulder 30. The auxiliary feed section 32 is located immediately in front of the feed section 28 and cooperates with the under face of the presser foot C between the right hand side wall 5^a of the opening 5 and the left hand 15 guide wall 20^a of the plate 20. Thus the auxiliary feed section 32 yieldably clamps the outer folded portion of the hem g at the right of the line of needle penetrations and cooperates with the presser foot to clamp the hem therebetween 20 and thereby prevent the setting of the stitches from curling or rolling the hem.

The presser foot C, in rear of the opening 5, is formed with a longitudinally extending opening 36 through which a top feed dog 37 projects and engages the hem g which has been stitched. This top feed dog may be of any suitable construction, although I preferably employ a 4-motion feed dog.

From the foregoing, it will be observed that 40 I have provided a blind stitch sewing machine with a hemmer attachment which is adjustable laterally not only to compensate for different weights of materials but also to vary the line of needle penetration at the hem relative to the inner edge of said hem, and that I have provided a main bottom feed for feeding the body fabric past the stitch forming mechanism and an auxiliary body feed which is yieldably mounted on the main feed for cooperation with the hem whereby hem folds of different thicknesses, due to different weights of materials, will be automatically accommodated. 45

It is of course to be understood that the details of structure and arrangements of parts may 55 be variously changed and modified without departing from the spirit and scope of my invention.

I claim:—

1. In a blind stitch sewing machine, the combination with a stationary presser foot having an opening, of a feeding means cooperating with the foot to feed the material rearwardly, a stitch forming mechanism including a reciprocating needle located above the foot and having its penetrating stroke in a plane extending across the line of feed, a ridge forming element for projecting a ridge of material upwardly through the opening of the foot and into the path of movement of the needle, the foot in 60 front of the opening thereof being provided with a rearwardly extending slot and with a groove 65 in the under surface of the foot in communication with the opening and slot, and a hemmer located in the slot in front of the groove and 70

including a core and a surrounding scroll respectively supported on the foot on opposite sides of the slot.

2. In a blind stitch sewing machine, the combination with a stationary presser foot having an opening, of a feeding means cooperating with the foot to feed the material rearwardly, a stitch forming mechanism including a reciprocatory needle located above the foot and having its penetrating stroke in a plane extending across the line of feed, a ridge forming element for projecting a ridge of material upwardly through the opening of the foot and into the path of movement of the needle, the foot in front of the opening thereof being provided with a rearwardly extending slot and with a groove in the under surface of the foot in communication with the opening and slot, a plate mounted on the foot for lateral adjustments in front of the opening thereof and on one side of said slot, and a hemmer located in the slot and including a core mounted on the foot on the side of the slot opposite the plate and a surrounding scroll mounted on said plate.

25 3. In a blind stitch sewing machine, the combination with a stationary presser foot having an opening, of a feeding means cooperating with the foot to feed the material rearwardly, a stitch forming mechanism including a reciprocatory needle located above the foot and having its penetrating stroke in a plane extending across the line of feed, a ridge forming element for projecting a ridge of material upwardly through the opening of the foot and into the path of movement of the needle, the foot in front of the opening thereof being provided with a rearwardly extending slot and with a groove in the under surface of the foot in communication with the opening and slot, a plate mounted on the foot for lateral adjustments in front of the opening thereof and on one side of said slot, and a hemmer located in the slot and including a core mounted on the foot on the side of the slot opposite the plate and a surrounding scroll mounted on said plate for lateral adjustments relative to the core.

4. In a blind stitch sewing machine, the combination with a stationary presser foot having an opening, of a feeding means cooperating with the foot to feed the material rearwardly, a stitch forming mechanism including a reciprocatory needle located above the foot and having its penetrating stroke in a plane extending across the line of feed, a ridge forming element for projecting a ridge of material upwardly through the opening of the foot and into the path of movement of the needle, the foot in front of the opening thereof being provided with a rearwardly extending slot and with a groove in the under surface of the foot in communication with the opening and slot, and a plate attached to the under surface of the foot at one side of the slot and including a vertical hem-guiding wall extending rearwardly along the slot, along the groove, and along the opening, and a hemmer located in the slot and mounted on the foot in front of the groove.

5. In a blind stitch sewing machine, the combination with a stationary presser foot having an opening, of a feeding means cooperating with the foot to feed the material rearwardly, a stitch

forming mechanism including a reciprocatory needle located above the foot and having its penetrating stroke in a plane extending across the line of feed, a ridge forming element for projecting a ridge of material upwardly through the opening of the foot and into the path of movement of the needle, the foot in front of the opening thereof being provided with a rearwardly extending slot and with a groove in the under surface of the foot in communication with the opening and slot, and a plate attached to the under surface of the foot for lateral adjustments relative thereto and at one side of the slot and including a vertical hem-guiding wall extending rearwardly along the slot, along the groove, and along the opening, and a hemmer located in the slot and including a core mounted on the foot on the side of the slot opposite the plate and a surrounding scroll mounted on said plate.

20 6. In a blind stitch sewing machine, the combination with a stationary presser foot having an opening, of a stitch forming mechanism disposed above the foot and including a reciprocatory needle movable across the opening, a ridge forming element for projecting a ridge of material upwardly through said opening into needle penetrating position, a hemmer disposed in front of the opening and in fixed relation to the foot, a bottom 4-motion feed cooperating with the foot to feed the body fabric and the hem rearwardly from the hemmer past the stitch forming mechanism, the feed including a vertically yieldable feed section disposed under the hem for co-operation therewith.

25 7. In a blind stitch sewing machine, the combination with a stationary presser foot having an opening, of a stitch forming mechanism disposed above the foot and including a reciprocatory needle movable across the opening, a ridge forming element for projecting a ridge of material upwardly through said opening into needle penetrating position, a hemmer disposed in front of the opening and in fixed relation to the foot, a bottom 4-motion feed cooperating with the foot to feed the body fabric and the hem rearwardly from the hemmer past the stitch forming mechanism, the feed including a main feed dog and a vertically yieldable auxiliary feed dog pivotally supported by the main feed dog to move therewith and disposed under the hem for cooperation therewith.

30 8. In a blind stitch sewing machine, the combination with a stationary presser foot having an opening, of a stitch forming mechanism disposed above the foot and including a reciprocatory needle movable across the opening, a ridge forming element for projecting a ridge of material upwardly through said opening into needle penetrating position, a hemmer disposed in front of the opening and in fixed relation to the foot, a bottom 4-motion feed cooperating with the foot to feed the body fabric and the hem rearwardly from the hemmer past the stitch forming mechanism, the feed comprising a main feed dog including a feed section extending along one side of the presser foot opening for engaging the body fabric and an auxiliary feed dog including a feed section extending along the other side of said opening for engaging the hem.

CHARLES W. MUELLER.
